UNITED STATES PATENT OFFICE.

WILLIE C. HICKEY, OF POTEET, TEXAS.

PLOW.

1,410,303.

Specification of Letters Patent. Patented Mar. 21, 1922.

Application filed March 15, 1921. Serial No. 452,526.

To all whom it may concern:

Be it known that I, WILLIE C. HICKEY, a citizen of the United States, residing at Poteet, in the county of Atascosa and State 5 of Texas, have invented new and useful Improvements in Plows, of which the following is a specification.

This invention relates to improvements in plows and has for an object the provision of 10 a plow having a plurality of spaced beams which are capable of relative adjustment so as to regulate the space between the plow blades.

Another object of the invention is the provision of a plow of the above character in which the plow beams are of novel construction, being formed of a single length of material and shaped to engage the axle of the plow, means being provided for clamping 15 the beams in position upon the axle to regulate the space between said beams, while additional means is provided for spacing the rear ends of the beams, to hold the latter in adjusted position.

25 Another object is the provision of a plow employing a plurality of plow beams, whose construction is of an exceedingly simple character, the result being a plow which may be manufactured at a low cost, or which may 30 be easily repaired when necessary.

The invention further includes novel means for mounting the plow handles, the entire plow being so constructed that it may be readily taken apart for shipment and 35 thereafter quickly and easily assembled.

With the above and other objects in view, the invention further includes the following novel features and details of construction, to be hereinafter more fully described, 40 illustrated in the accompanying drawings and pointed out in the appended claim.

In the drawings:—

Figure 1 is a side elevation of a plow embodying the present invention.

45 Figure 2 is a plan view of the same.

Figure 3 is a central vertical sectional view.

Figure 4 is a rear view.

Figure 5 is a detail view of one of the 50 plow beams.

Referring in detail to the drawings, wherein like characters of reference denote corresponding parts, the plow is shown as comprising an axle 10, which is supported upon 55 wheels 11. Secured to the axle is a plurality of plow beams 13, the said beams being of

novel construction. They are preferably formed from a single length of material and have their forward ends bent to provide axle receiving loops 13', the latter being adapted 60 to hook over the axle and being provided with an adjusting screw 14, which, when joined will act to bind the loops upon the axle and prevent longitudinal movement thereon. The rear lower ends of the beams 65 are adapted to have secured thereto suitable plow blades or shovels 15, although cultivator teeth may be substituted for these shovels if desired.

The rear ends of the beams are held in 70 proper spaced relation through the medium of a spacing bar 16, which is provided with spaced openings 17 for the reception of a hook bolt 18. This bolt is adapted to be engaged beneath the lower edge of the beam 75 and to pass through one of the spaced openings 17 for the reception of a nut, which when joined will hold the bar 16 and the beam properly associated. All of the beams are of similar construction, except the outer 80 beams are preferably curved as shown so as to permit of a wider range of adjustment.

Secured to the plow are handles 19, the latter having their forward ends provided with openings for the reception of the adjusting screw 14 of the central beam, so that this screw serves the double purpose of holding the central beam and the axle and of securing the forward ends of the handles in place. The handles are braced by rods 20 90 which connect them with the spacing bar 16, while additional rods 21 serve to connect the said handles with the central beam 12.

In order to provide means for securing a draft animal to the plow, there is secured to 95 the axle a pair of shafts 22.

It will be seen from the foregoing description and the accompanying drawings that the invention provides a plow of an exceedingly simple character, in which there 100 is employed a plurality of plow beams, capable of relative adjustment. The construction is such that the plow may be readily disassembled for shipment or repair.

The invention is susceptible of various 105 changes in its form, proportions and minor details of construction and the right is herein reserved to make such changes as properly fall within the scope of the appended claim.

Having described the invention what is 110 claimed is:—

A plow embodying a wheel supported axle,

a plurality of plow beams secured thereto, said beams each having a loop at their forward ends for engagement around the axle, means whereby the loop may be adjustable to adjust the relative positions of the plow beams, a spacing bar adjustably secured to the rear ends of the plow beams to hold the

latter in position, handles having their forward ends secured to the adjusting means of one of the loops and braces connecting the 10 handles with the spacing bar.

In testimony whereof I affix my signature.

WILLIE C. HICKEY.
